CLAIM

The ornamental design for a prolate spheroid device, as shown and described.

DESCRIPTION

FIG. 1 is a perspective view showing the prolate spheroid device embodying the new design;

FIG. 2 is a front elevation view thereof;

FIG. 3 is a left side elevation view thereof, the right side elevation being the mirror image;

FIG. 4 is a top plan view thereof;

FIG. 5 is a bottom plan view thereof;

FIG. 6 is a front elevation view of a variation of the prolate spheroid device; and,

FIG. 7 is a left side elevation view thereof, the right side elevation being the mirror image.

The broken lines in the drawing views are included for the purpose of illustrating unclaimed environment only, and forms no part of the claimed design.

The broken lines in the drawings depict environmental subject matter only and form no part of the claimed design. The dot dash lines in the drawings represent the bounds of the claim and form no part of the claimed design.
